INTERLOCKING MONOGRAM LABEL

Filed June 29, 1926

FIG. 1

INVENTOR.
GEORGE F. STANLEY
BY *Paulmin Paulmin*
ATTORNEYS.

UNITED STATES PATENT OFFICE.

GEORGE F. STANLEY, OF DAYTON, OHIO, ASSIGNOR, BY MESNE ASSIGNMENTS, TO THE STANLEY MANUFACTURING COMPANY, OF DAYTON, OHIO, A CORPORATION OF OHIO.

INTERLOCKING MONOGRAM LABEL.

Application filed June 29, 1926. Serial No. 118,429.

My invention relates to labels and in particular to an interlocking label.

It is the object of my invention to provide interlocking labels which, when interlocked, will not only render mutual aid and assistance to one another in retaining their position on the supporting surface and with respect to one another, but it will also present such an appearance that the several interlocked labels will appear as one.

My invention is particularly adaptable to monograms and in such a combination it would be obviously impractical as well as very expensive to provide monograms for each person having a separate die for each monogram.

I have overcome this difficulty by having twenty-six large letters of the alphabet and twenty-six small letters of the alphabet, and then provide this interlocking combination between the small and large letters forming monograms, which, when mounted upon the supporting surface, appear to be made out of a single piece of stock, thereby providing an attractive monogram at a relatively low cost.

It will be understood that a part of my combination is making such labels and mounting them in interlocked condition out of a combined metal, glue and paper, which constitute a part of my invention.

It will be understood that I have also provided additional features of strong margins or ridges which form broad abutting shoulders against which the adjacent shoulders of the adjacent label may abut.

My invention is especially adaptable to monograms for automobiles, where the labels are subjected to severe conditions of weather, usage and repeated washing.

Referring to the drawings:

Figure 1 is a top plan view of one of the large size labels;

Figure 2 is a top plan view of a small label;

Figure 3 is a similar view of a similar label in the same small series;

Figure 4 is a top plan view of the assembled labels fastened in interlocked condition;

Figure 5 is a section on the line 5—5 of 50 Figure 4.

Referring to the drawings in detail, it will be understood that each label is composed of an upper metal plate 1 properly formed with the configurations or embossing 55 of initials, and the like, mark 2, the margin of the metal having an embossed margin 3.

The under side of the label is prepared with a layer of glue 4, to which is attached a layer of paper 5 on the bottom of which 60 is a layer of glue 6. The stock is composed of a sheet of metal, glue, paper and glue, and from this stock the label is sheared and embossed.

It will be noted that the marginal embossing 3 provides a broad shoulder 8 against which the adjacent labels have their shoulders 8 engage.

It will be noted that the arcuate sides 7 of the small labels engage within the arcuate 70 cutaway sides 10 of the large label. When placed in position the small labels cannot move up or down nor can the three labels move relative to one another because of the projecting shoulders 8 and 9 on the large 75 label.

It will be understood that I desire to comprehend within my invention such modifications as may be necessary to adapt it to varying conditions and uses.

Having thus fully described my invention, what I claim as new and desire to secure by Letters Patent, is:—

1. In combination, a main label and a supplementary label, said labels having oval shaped portions engaging one another, the line of contact being along said oval shaped portions to prevent relative movement, said labels being so arranged that, when they are positioned with respect to each other, they appear to be a single label.

2. In combination, a main label having an adhesive back and a concave side, a supplementary label having a convex side adapted to fit in the concave side, said supplementary label and main label having a non-circular shape where the concaved and convex sides adjoin, whereby relative turn-

ing movement between said labels is prevented, said second label having an adhesive back and a common supporting surface to which said labels are attached.

3. In combination, a main label having curved sides, and supplementary labels having convex sides fitting therein, said three labels having adhesive backs, and a

common supporting surface for said interlocking labels, the contacting curved surfaces of said labels being of non-circular configuration whereby relative turning movement of said labels is resisted by said curved surfaces. 10

In testimony whereof, I affix my signature.
GEORGE F. STANLEY.
